ELECTRONIC DEVICES

Olof Erik Hans Rydbeck, Goteborg, Sweden

Application March 13, 1956, Serial No. 571,277

Claims priority, application Sweden March 18, 1955

8 Claims. (Cl. 315—5.15)

The present invention relates to an electronic device with at least two cooperating electron beams. The problem to be solved by the invention was to investigate whether and under what conditions a cooperation can take place between two intersecting electron beams, i.e. a cooperation that can be used in practice, particularly in such cases where the use of known arrangements is limited. Thus, the object of the invention is to provide an electronic device in which these conditions are fulfilled or may be fulfilled in a simple manner.

An electronic device according to the invention is characterized by means for generating a first electron beam, means for generating a second electron beam, a space, preferably of wave-guide character, in which the beams are caused to intersect each other, and means for imposing upon the first and/or the second beam such electron velocity or other character that a desired cooperation between the beams, e.g. for amplification, attenuation, generation of oscillations etc., is obtained.

A device according to the invention may be carried out in different ways and two types will be described hereinafter having different operations in certain respects, with reference to the accompanying drawings. The drawing figures illustrate schematically the structural features of the embodiments.

Fig. 1 shows one embodiment of a device according to the invention.

Fig. 2 is a sectional view of a wave guide incorporated in the device according to Fig. 1. Fig. 3 is a sectional view of an alternative form of wave guide to that shown in Fig. 2.

Fig. 4 shows another embodiment of the invention.

Fig. 5 shows still another embodiment of the invention.

Figs. 6 and 7 show alternative embodiments of the wave guides of the device.

In the first type of the device according to the invention a velocity modulation is imposed upon one of the two electron beams, which hereinafter is denoted as the first electron beam, said modulation being obtained, for instance, by means of a modulation helix or a cavity resonator, whereafter the beam is caused to pass through said space having wave guide character, where it is intersected perpendicularly by the second electron beam, which is homogeneous and in which the electron velocity is adjusted to a suitable value.

The other type of the device according to the invention differs from the above-mentioned first type in that the second electron beam is not homogeneous, i.e. has not a constant electron density, seen in the direction of the first electron beam, but has a periodically varying electron density.

In both said types amplification of the oscillations imposed by modulation of the first electron beam may be obtained under certain conditions which will be more definitely stated in the following.

In the device according to Fig. 1 which belongs to the first type, a first electron beam I is generated by an electron gun 3 together with electron optical means for pro-

2

ducing a homogeneous beam of parallel electron rays passing in the axial direction through a wave guide 1 to a collector 5. The beam I is modulated in velocity when passing through a resonator system 7 of any conventional construction having an input 9 for a coupling lead. A resonator system 11 at the end of the wave guide through which system the electron beam passes serves as an output resonator from which the oscillations may be taken which are obtained from the electron beam I after its passage through the wave guide. The hatched parts of the drawing figures designate insulating material (glass).

In the shown embodiment the wave guide 1 has rectangular cross section as shown in Fig. 2 which corresponds to the sectional line A—A in Fig. 1, said cross section being substantially wholly occupied by the electron beam I. This beam has previously been formed to a corresponding shape by the electron optical means referred to in connection with the electron gun. The one longitudinal side 15 of the wave guide is provided with a great number of apertures through which the electrons of the second electron beam II which is perpendicular to the first electron beam I and is designated as the cross beam in the following description may pass into the wave guide. The apertures in the wall 15 are so small that the character of the device 1 as a wave guide for the high frequency oscillations of the electron beam I is not lost. The side wall 15 may either be galvanically connected to the rest of the wave guide or may be galvanically but not for high frequencies insulated from the rest of the wave guide as will be described in more detail hereinafter.

The cross beam II is generated by a cathode 17 extending parallel to the wall 15 at a suitable distance therefrom. The acceleration voltage for the electrons of the cross beam may be applied between the cathode 17 and the wave guide 1, and furthermore one or more control grids 19 may be arranged between the cathode 17 and the wall 15 as in the shown embodiment.

It has now been found that in the embodiment shown in Fig. 1 an amplification of the oscillations modulated upon the electron beam I is obtained owing to cooperation between the beam I and the cross beam II, if the velocity v_2 of the electrons of the cross beam is adjusted approximately to a such value that

$$v_2/c_0 = 2a/n\lambda_0$$

where:

c_0 =the velocity of light

a =the cross dimension of the wave guide in the direction of the cross beam

λ_0 =the wave length in vacuum of the oscillations

n =an integer 1, 2, 3 etc.

The acceleration voltage V_2 which is required for accelerating the electrons of the cross beam to the velocity v_2 may suitably be adjustable in a manner known per se and, furthermore, it is possible to adjust the velocity of the electrons in the shown embodiment by varying the potential of the control grid 19.

The mechanism of the process resulting in an amplification of the oscillations of the electron beam I is difficult to illustrate in another way than by a relatively complicated mathematical treatment which, applied to a device having a wave guide with rectangular cross section, gives as result the conditions stated above. Thus, this condition is true substantially only in such cases where the cross section of the wave guide is rectangular and, besides, under the other conditions mentioned above.

In order that the velocity v_2 of the electrons of the cross beam may be constant and equal substantially everywhere in the wave guide which condition is difficult to fulfill in a wave guide in which the wall provided with

the apertures is galvanically connected to the rest of the wave guide owing to space charge effects tending to deflect and retard the electrons in the wave guide, it may be suitable to insulate the wall 15 from the rest of the wave guide with respect to direct current for instance in the manner shown in Fig. 3, where the wall 15 is connected to or provided with flanges 21 which together with the wave guide body and an interposed insulating dielectric 23 form a capacitance serving substantially as a short-circuit for the high frequency currents in the wave carrier mantle, a suitable voltage difference being applied between the wall 15 and the wave carrier body 1 for maintaining a desired velocity and direction of the electrons of the cross beam at a constant value, which is desired in order that the above mentioned condition shall be fulfilled substantially everywhere in the wave guide.

It can be shown that the band width $2\Delta\omega/\omega_0$ of the amplification, where ω_0 is the angular frequency in vacuum of the oscillations modulated upon the primary electron beam I roughly corresponds to the expression

$$2\Delta\omega/\omega_0 = \omega_p^{(2)}/\omega_0$$

where $\omega_p^{(2)}$ is the plasma angle frequency of the cross beam.

In the following example it has been supposed that the vacuum wave length λ_0 is 20 cm. When in the expression for the amplification above n is chosen to be equal to 1 (the lowest mode of oscillations) one arrives with $a=1$ to the expression $v_2/c_0=0.1$. Since

$$v_2 = \sqrt{\frac{2eV_2}{m}}$$

where V_2 is the acceleration voltage for the cross beam, and e and m are the charge and the mass respectively of the electron, the condition for amplification will be fulfilled at a value of V_2 of the order of 2500 v.

As an example as to the band width it is assumed that the vacuum wave length is 20 cm. as above, while the current density of the cross beam is approximately 0.5 ma./mm.² and the acceleration voltage for the cross beam is approximately 1000 v. In this case a band width may be obtained which is roughly equal to $1/2\pi$, which can be considered as a very high value and is sufficient in most connections.

In the described embodiment it was assumed that only the electron beam I was subjected to modulation (velocity modulation). However, it is possible to modulate also the cross beam II with another frequency, in which case a frequency mixing operation may be obtained, the resulting signals being taken from the resonator 11 according to the drawing.

If the frequency modulated upon the cross beam is considerably lower than the high frequency modulated upon the electron beam I the higher frequency may be modulated by the lower frequency by interaction between the two beams in the wave guide, the modulated high frequency being taken from the resonator 11 as in the case just mentioned.

In analogy with the conditions in conventional amplifier tubes it is, of course, possible to use feedback in the device according to the invention, it being possible to bring the device into self-oscillations (as an oscillator) by coupling the resonators 7 and 11 to each other in a sufficient degree in a manner known per se.

The condition for obtaining amplification as stated above is fundamentally independent of the intensity, i.e. the current density of the cross beam. A variation of this current density will thus not change materially the conditions for obtaining amplification but it will have an influence upon the resulting band width in such manner, that the band width is substantially proportional to the square root of the current density.

In the drawings no means for supplying electrode poten-

5

tials, for cathode heating etc., are shown, since these means may be of any conventional construction.

Fig. 4 shows schematically a device of the other type of the invention in longitudinal section. The figure shows only the wave guide 1 with the wall 15 which is permeable to electrons and further the means for the generation of the cross beam II, it being assumed that the device in other respects corresponds to the one shown in Fig. 1. In the device shown in Fig. 4 the first electron beam I is homogeneous and subjected to velocity modulation as in the type described above. However, the cross beam II is not homogeneous but has an electron density which varies in the direction of the electron beam I, as is illustrated by the curve 33 in Fig. 4, the variation being periodic with the "structure" wave length λ_s . This variation may be obtained in different ways for instance by using a control grid 31 with periodically varying pitch or "Durchgriff" (shielding factor) as according to Fig. 4, but the variation may also be obtained in other ways, for instance by using a cathode 17 having periodically varying electron emission ability.

It has been found that in such a device it is possible to obtain amplification of the oscillations modulated upon the electron beam I by interaction between the electron beam I and the cross beam II in the wave guide 1, said amplification being independent of the electron velocity of the cross beam, if

$$\lambda_s = \lambda_p/2$$

where λ_p is the plasma wave length of the electron beam I, said condition being true for the embodiment shown schematically in Fig. 4. In other words this expression means that in Fig. 4 $b-a=\lambda_p/4$, where a and b are the distances from the input end of the wave guide 1 to the adjacent minimum and maximum respectively of the main component (fundamental) of the cross beam II. For optimal amplification the distance a should be chosen so that $a=\lambda_p/8$. If $b=\lambda_p/8$, which may be fulfilled for instance by shaping the control grid 31 or the cathode in a suitable manner, a weakening or attenuation of the oscillations is obtained instead of amplification. However, in certain cases also such weakening may be useful in practice.

If λ_s does not satisfy the condition stated above an amplification may be obtained only if the electron velocity in the cross-beam is adjusted to a suitable value. Such adjustment may be effected in the manners described in connection with Fig. 1.

Further, it should be pointed out that it is not necessary that the variations of the electron density of cross beam II in the direction of the electron beam I strictly follow a sine curve, since the wave form of the variation may be of other shape, as is indicated in Fig. 4 by means of a dashed curve, it being sufficient that the variation has a component (especially a fundamental) the wave length of which fulfills the above condition in order that the electron velocity of the cross beam shall not be critical with respect to the amplification. Thus, it may be possible to obtain the variation of the current density by arranging instead of the control grid 31 a number of screens or the like in a regular mutual distance $\lambda_s=\lambda_p/2$ in the direction of the electron beam I or by using a plurality of shorter cathodes 17 distributed regularly in the same manner along the electron beam I. As an alternative also the wall 15 may be shaped in such manner that it can pass electrons only in certain zones regularly distributed in the manner described.

Also this type of the device according to the invention offers the previously stated possibilities as to feedback and modulation of the cross beam (for frequency mixing and modulation of the primary beam I).

According to the invention it is possible by modifying the electric conductance of the conducting inner surface of the wave guide to change the band width of the amplification obtained. Thus, it would be possible to increase

70

75

this band width, though on the cost of the maximum amplification, in this band by applying graphite on the inner surface of the wave guide or by treating this surface in another way for reducing its conductance.

The amplification obtained in a device according to the invention is dependent upon the length 1 of the wave guide, i.e. its dimension in the direction of the primary beam I, so that the total amplification may be calculated as the amplification per unit length of the wave guide multiplied with the length of the wave guide. It is not necessary that the amplification per unit length is constant along the wave guide. Thus it is possible by arranging several electrode systems or electrodes, for instance several control grids or cathodes, for the generation of several cross beams, to obtain an amplification which depends upon as many factors as the number of different electrode systems and electrodes respectively for cross beams, so that the amplification may be influenced by several different signals each applied to one of said electrode systems or electrodes. Such a device may be suitable for instance for modulation (or impulsation) of a carrier frequency by several independent signals. Fig. 5 shows schematically a device of this kind, only the wave guide of the tube and the means for generating cross beams being shown in longitudinal section as in Fig. 4. Fig. 5 shows four electrode systems A, B, C and D having cathodes 35 and grids 37 for the generation of the cross beams II_A, II_B, II_C and II_D but fewer or more systems may of course be used. Each electrode system A-D will evidently cooperate with and effect the primary beam I independently of the other electrode systems, so that the output signal obtained from the beam I will contain components derived from the different signals applied to the systems A-D. These systems may fundamentally be of any desired type, for instance either of the type shown in Fig. 1 or of the type shown in Fig. 4 or of both types.

The arrangement shown in Fig. 5 for influencing a primary beam I by means of different signals may of course be modified in different ways without fundamentally changing its function. Thus, it is possible to arrange instead of several cathodes or grids either a single long cathode and several control grids or several cathodes and a single control grid. Further it is not necessary that the electrode systems A-D are arranged side by side, but the cross beams may be directed into the primary beam I from different directions and, if desired, in a single area, which may be suitable in certain cases, for instance in view of structural facilities.

The embodiments shown in Figs. 1-5 are provided with a space in the form of a wave guide 1, in which the electron beams I and II cooperate. The desired cooperation, however, is not necessarily limited to the use of a space of this character, since a cooperation is always obtained in the area in which the beams intersect each other under the previously stated conditions relating to the circumstances in a device having two perpendicular electron beams. In this connection it is important to point out that it is not necessary that the two beams are exactly perpendicular, since, fundamentally, a cooperation occurs even if the cross beam has only a velocity component perpendicular to the primary beam. Since the mutual cooperation between two parallel and mutually coupled electron beams is previously known, there may be, in a device according to the invention with beams obliquely intersecting each other, a question of superposition of two effects arising from the cooperation between the primary beam and the component parallel therewith and the component perpendicular thereto respectively of the cross beam.

Though the wave guide 1 in the embodiments shown in Figs. 1-5 were assumed to be rectangular in cross section, it may be preferred to use another form of wave guide. The condition for obtaining the desired cooperation between the electron beams mentioned in connection

with Fig. 1 may then have another form than that stated above. In such cases where it is difficult to calculate theoretically said condition there remains always—as stated above—the possibility of obtaining the conditions for the desired cooperation by varying the potentials of the electrode systems of the two electron beams. Figs. 6 and 7 show examples of two alternative embodiments with circular wave guides and a corresponding form of the electrode system for the cross beam.

- 10 According to Fig. 6 the wave guide consists of two coaxial cylindric walls 41 and 43 the inner wall 43 being permeable to electrons in the same manner as the wall 15 in Figs. 1 and 5. In the zone-formed space in the wave guide an axial electron beam passes which constitutes the primary beam I. A cross beam II is generated by the cathode 45 in the center of the wall 43, a control grid 47 being provided around the cathode for controlling the electron velocity of the cross beam for modulation or impulsation of same.
- 15 20 In the device according to Fig. 7 the wave guide consists of an inner cylindrical wall 51 and an outer wall 53 coaxial therewith and having perforations, the primary beam I passing axially between said walls. From an outer, cylindrical cathode 55 a cross beam II passes 25 through the wall 53 into the wave guide 51, 53 in which the desired cooperation between the beams takes place. Also in this arrangement one or more control grids 57 may be arranged between the cathode 55 and the wall 53 which is permeable to electrons.
- 30 35 The invention is not limited to the embodiments described and shown, since these embodiments may be modified in the abovementioned respects and also in other respects within the scope of the invention.

What I claim is:

- 35 40 45 1. An electronic device comprising a wave guide having a space therein, a first source of charged particles positioned to direct a stream of said particles axially along said wave guide space, a second source of charged particles positioned to direct a second stream of charged particles substantially at right angles to said first stream of particles along a substantial portion of said wave guide, and means for varying said second stream of charged particles to modulate said first stream of charged particles, said second electron beam having a velocity component v_2 which approximately fulfills the condition

$$v_2/c_0 = 2a/n\lambda_0$$

where:

- 50 55 60 65 70 c_0 =the velocity of light
 a =the cross dimension of the wave guide in the direction of the cross beam
 λ_0 =the wave length in vacuum of the oscillations
 n =an integer.

- 55 60 65 70 2. An electronic device comprising a hollow wave guide having a circular cross section, a first source of charged particles positioned to direct a stream of said particles axially along said wave guide, a second source of charged particles positioned to direct a second stream of charged particles substantially at right angles to said first stream of particles along a substantial portion of said wave guide, and means for varying said second stream of charged particles to modulate said first stream of charged particles comprising a second cylindrical member concentrically arranged within said wave guide intermediate said second source of charged particles and said stream of charged particles produced by said first source, the walls of said second cylindrical member being permeable to the particles of said second source.
3. An electronic device comprising a hollow wave guide, a first source of charged particles positioned to direct a stream of said particles axially along said wave guide, a second source of charged particles positioned to direct a second stream of charged particles substantially at right angles to said first stream of particles along a sub-

stantial portion of said wave guide, and means for varying the current density of said second stream of charged particles to modulate said first stream of charged particles comprising a control grid positioned intermediate said second source and said first stream of particles, and means for periodically varying the shielding factor of said control grid.

4. An electronic device comprising a hollow wave guide, a first source of charged particles positioned to direct a stream of said particles axially along said wave guide, a second source of charged particles positioned to direct a second stream of charged particles substantially at right angles to said first stream of particles along a substantial portion of said wave guide, and means for varying the current density of said second stream of charged particles to modulate said first stream of charged particles, comprising means for periodically varying the emission ability of said second source.

5. An electronic device comprising a hollow wave guide, a first source of charged particles positioned to direct a stream of said particles axially along said wave guide, a second source of charged particles positioned to direct a second stream of charged particles substantially at right angles to said first stream of particles along a substantial portion of said wave guide, and means for varying the current density of said second stream of charged particles to modulate said first stream of charged particles, the wave length of the variation of the current density of said second stream of charged particles as seen in the direction of the first stream of charged particles being approximately equal to half the plasma wave length of the first stream of charged particles.

6. An electronic device as defined in claim 5 wherein the distance between the input end of said wave guide and the nearest minimum or maximum peak of the main component of the variation of the current density of the second stream of charged particles is equal to $\frac{1}{8}$ of the plasma wave length of the first stream of charged particles.

7. An electronic device comprising a hollow wave guide, a first source of charged particles positioned to direct a stream of said particles axially along said wave guide, a plurality of auxiliary sources of charged particles arranged to direct second streams of said particles at right angles to said first stream of particles, and means for applying control signals to each of said auxiliary sources to periodically vary the current densities of said second particle streams and thus modulate said first stream of particles.

8. An electronic apparatus comprising a wave guide having a rectangular cross-section, an electron gun positioned to direct a first stream of electrons axially within said wave guide, one longitudinal side of said wave guide being permeable to electrons, a cathode parallel to and spaced from said permeable longitudinal wave guide side, said cathode extending substantially the length of said permeable wave guide side, circuit means causing said cathode to produce a second stream of electrons through said permeable wave guide side at right angles to said first stream of electrons substantially along the length of said wave guide, and means for periodically varying the density of said second stream of electrons to modulate said first stream of electrons comprising a control grid intermediate said cathode and said permeable longitudinal wave guide side, said control grid having a length substantially equal to the length of said cathode, the periodic variation of current density of said second stream of electrons being effected by a periodic variation of the effective shielding factor of said control grid.
